CLAIM

I claim the ornamental design for a watch, as shown and described.

DESCRIPTION

FIG. 1 is a left perspective view of a watch showing my new design;

FIG. 2 is a right perspective view thereof;

FIG. 3 is a front elevation view thereof;

FIG. 4 is a back elevation thereof;

FIG. 5 is a left-side elevation view thereof;

FIG. 6 is a right-side elevation view thereof;

FIG. 7 is a top plan view thereof; and,

FIG. 8 is a bottom plan view thereof, showing the watch. The broken lines showing the strap, battery cover, crown, pushers, and internal workings are included for the purpose of illustrating environmental structure and form no part of the claimed design.
